UNITED STATES PATENT OFFICE.

JOHN McDONALD HATTERSLEY, OF BIRMINGHAM, ENGLAND.

FOLDING STEREOSCOPE.

1,392,327.

Specification of Letters Patent.

Patented Oct. 4, 1921.

Application filed October 20, 1920. Serial No. 418,296.

To all whom it may concern:

Be it known that I, JOHN McDONALD HATTERSLEY, a subject of the King of Great Britain, residing at 57 County Chambers, 5 66 Corporation street, Birmingham, in the county of Warwick, England, have invented a certain new or Improved Folding Stereoscope, (for which I have filed an application in England, Patent No. 159,243, 10 October 9, 1919,) and I do hereby declare that the following is a full, clear, and exact description of the same.

This invention relates to stereoscopes of the folding type and has for its object to 15 provide an improved and simplified construction.

A stereoscope constructed according to the present invention comprises a hood or eye piece carrying a pair of lenses, and a 20 member adapted to carry the cards or pictures, which member is attached to the hood by lazy tongs or their equivalents so that it can be moved toward or away from the forward end of the hood or may be made to 25 engage with said end to form a closure therefor.

Referring to the drawings:—

Figure 1 is a perspective view of a stereoscope according to the invention in its ex- 30 tended condition.

Fig. 2 is a longitudinal section of the same.

Fig. 3 is a transverse section of the stereoscope collapsed.

Fig. 4 is a view in elevation illustrating the hood portion.

In the construction illustrated upon the accompanying drawings, the hood or eye piece 1 is made of sheet metal and has both 40 ends open, the rear end 2 being shaped to fit around the forehead and face adjacent the eyes. The edge of the hood adjacent to the face may be padded as indicated at 3 with leather or the like or this edge may 45 be beaded over.

A pair of lenses 4 are carried by two members, one of which 5 extends transversely across the interior of the hood and supports the rear faces of the lenses. The 50 other member 6 is centrally disposed with respect to the member 5 and has recessed portions adapted to receive and support the front and side portions of the lenses, the member 6 has tongues 8 or their equivalents adapted to pass through slots in the member 5 whereby the former is secured. It will be understood that only one member

may be employed having suitable projecting portions to engage the edges of and retain the lenses. This lens carrying member 60 6 may be made of sheet metal and may be held in the hood at the bottom by means of tongues 9 on a plate hereinafter referred to which engage slots in the member 5 and at the top by means of an abutment 27 65 formed by pressing out the hood at the top or the member 5 may fit in an internal groove formed by pressing the sheet metal of the hood.

The forward member 10 of the stereoscope which is adapted to carry the cards or pictures 11 indicated by dotted lines in Fig. 1 is shaped so that it is adapted to fit on to the forward end of the hood and to form a closure therefor. For this purpose 70 75 the forward member has a flange 12 at its edge adapted to fit over the forward edge 13 of the hood member in the manner of a lid of a tin box.

The card or picture carrying member is 80 attached to the hood by lazy tongs 15 or equivalent means may be employed enabling it to be moved toward or away from the hood member and at the same time to preserve a steady support. If lazy tongs are 85 employed as in the construction illustrated these may be adapted to fold up and fit within the hood member in a sheet metal casing formed by a plate 26 which is bent to channel section at the bottom thereof as 90 shown at Fig. 3. The lazy tongs may be attached to two pivoted arms 16 connected to a sheet metal plate 17 forming part of the picture carrying member, while near the forward end the lazy tongs may be connected to said plate by a pin 18 which engages with a slot in the plate.

The rear end of the lazy tongs has a pair of arms 22 pivoted on the plate 26 secured within the hood portion, the plate having a 100 slot 23 which is engaged by a pin 24 on the links or the lazy tongs.

The card or picture carrying member is provided with means whereby a card or picture may be supported therein in the required position which in the construction illustrated takes the form of a pair of arms 18 pivoted on the aforementioned plate 17, the said arms projecting outwardly when the device is extended but adapted to fold 110 inwardly so as to be with the hood portion when collapsed. The ends of the said arms project upwardly and inwardly while their extremities 19 are bifurcated to receive the

card, a stop 20 also being provided on the arms adjacent the ends to hold the card erect. The said member may be provided with holes or a projecting handle whereby it may be moved into the required position in relation to the hood member. The picture may be supported at the vertical edges by two brackets including channel section members.

10 As previously stated the picture carrying member normally forms a closure for the forward end of the hood member, but when required for use this picture carrying member is moved away from the forward end 15 of the hood and a picture is inserted. The distance between the picture and the lenses carried by the hood can then be adjusted as desired.

Instead of using lazy tongs, equivalent 20 jointed or telescopic or expandible members may be employed.

What I claim then is:

1. A folding stereoscope comprising a rigid hood member, a flange on the forward 25 end of said hood member, a lens carrying member within said hood having a pair of lenses, a rigid picture carrying member corresponding in shape with the hood member, a flange on the rear end of said picture 30 carrying member adapted to fit around the flange on the hood member and form a closure therefor, and extensible connecting means secured to said hood and to said picture carrying member whereby the picture 35 carrying member can be extended for use.

2. A folding stereoscope comprising a rigid hood member, a flange on the forward end of said hood member, a lens carrying member within said hood having a pair of 40 lenses, a rigid picture carrying member corresponding in shape with the hood member, a flange on the rear end of said picture carrying member adapted to fit around the flange 45 on the hood member and form a closure therefor, lazy tongs secured to said hood and to said picture carrying member and having an independent pin and slot connection with a plate disposed within said hood and said member whereby the picture carrying member 50 can be extended for use, and a fixed partition member within the said hood having a slot adapted to receive a projection on the lazy tongs.

3. A folding stereoscope comprising a rigid sheet metal hood member, a flange on 55 the forward end of said hood member, a sheet metal lens carrying member within said hood having a pair of lenses, an abutment carried by the hood adjacent the top 60 of the lens carrying member adapted to support the top thereof, a partition member within the said hood, tongues carried by said partition member engaging with slots in the bottom of the lens carrying member to secure 65 the bottom end thereof, a rigid sheet metal

picture carrying member corresponding in shape with, adapted to fit over and form a closure for the forward end of the hood member, a flange on the rear end of said picture carrying member adapted to fit 70 around the flange on the hood member and form a closure therefor, lazy tongs secured to said hood and to said picture carrying member, and having an independent pin and slot connection with said partition member 75 and with the picture carrying member, whereby the picture carrying member can be extended for use.

4. A folding stereoscope comprising a rigid hood member, a flange on the forward 80 end of said hood member, a lens carrying member within said hood having a pair of lenses, a rigid picture carrying member corresponding in shape with the hood member, a flange on the rear end of said picture carrying member 85 adapted to fit around the flange on the hood member and form a closure therefor, lazy tongs secured to said hood and to said picture carrying member, a partition member within the said hood having a slot adapted to receive a projection on the lazy tongs, a plate carried by said picture carrying member having a slot adapted to receive a projection on the lazy tongs, and a pair of pivoted arms carried by the plate 90 on the picture carrying member adapted to normally lie within the hood portion, but to project outwardly when the member is extended to carry the pictures.

5. A folding stereoscope comprising a rigid sheet metal hood member, a flange on the forward end of said hood member, a sheet metal lens carrying member within said hood having a pair of lenses, an abutment carried by the hood adjacent the top 100 of the lens carrying member adapted to support the top thereof, a rigid sheet metal picture carrying member corresponding in shape with the hood member, a flange on the rear end of said picture carrying member 105 adapted to fit around the flange on the hood member and form a closure therefor, lazy tongs secured to said hood and to said picture carrying member whereby the picture carrying member can be extended for use, a partition member within the said hood having a slot adapted to receive a projection on the lazy tongs, tongues on the bottom of said 110 partition member engaging with slots in the lens carrying member to secure the said bottom thereof, a plate carried by said picture carrying member having a slot adapted to receive a projection on the lazy tongs and a pair of pivoted arms carried by the plate on the picture carrying member adapted to normally lie within the hood portion, but to project outwardly when the member is extended to carry the picture.

In witness whereof I affix my signature.
JOHN McDONALD HATTERSLEY.
